TWO-ROLL TYPE CRUSHER-FEEDER

Frank H. Nickle and Arthur G. Nickle,
Saginaw, Mich.

Application January 19, 1946, Serial No. 642,345

7 Claims. (Cl. 241—141)

1

This invention relates to two-roll type crusher-feeders adapted for reducing bulk or lump materials and feeding the reduced product at any desired rate of flow to pulverizing mills or other processing equipment requiring a steady influx.

A specific application is the crushing and feeding of ear corn to feed-grinding mills. Also, this invention relates to a machine adapted for reducing materials to a predetermined size, such as the reduction of whole corn cob to a uniform size suitable for poultry litter. For either purpose, the construction is identical, as it is characteristic of roll type crusher-feeders that the reduced product becomes finer when the rate of efflux is reduced, and contrawise, coarser when the rate of flow is increased.

The primary object of this invention is to provide a flow-controlling mechanism for a two-roll ear corn crusher or the like which may be manually adjusted with little effort to vary the rate of output and the fineness of the reduced material.

Another object is to provide a valve mechanism which remains in set position despite the tendency of the outgoing materials to crowd the valves open.

A further object is to provide a rigid supporting and clamping means for the stationary shearing element which co-acts with the rolls when the material is being reduced.

In the drawings:

Fig. 1 is a fragmentary plan view of a two-roll type crusher-feeder in which our invention is embodied, the housing, rotative elements and other parts being broken away to more clearly show the flow-control mechanism.

Fig. 2 is a transverse sectional elevation taken on line 2—2 of Fig. 1.

Fig. 3 is a longitudinal sectional elevation taken on line 3—3 of Fig. 2.

Fig. 4 is an exploded isometric fragmentary view showing the flow-control mechanism, the broken lines showing range of movement of valve plates.

In the drawings, numerals 10 and 11 designate end and side walls respectively of a rectangular housing H that receives bulk materials (not shown). The end walls 10 are made to support flanged bearings 12 in which a pair of roll shafts 13 and 14 are journaled, these shafts projecting outwardly on one end to receive intermeshing gears 15 that make rolls coating, the direction of rotating being as indicated by arrows in Fig. 2 of the drawings.

The roll shafts 13 and 14 carry teeth 16 for

2

reducing material by action of the peripheral cutting edges 17 traveling in close relation to stationary shear bar 18, which bar is centrally disposed between the rolls and adapted to receive impact from the teeth on either roll.

The shear bar 18 is mounted upon a cross bar 19 that spans the housing H in parallel symmetrical relation to the shear bar and forms the middle portion of the bottom structure. Underlying and supporting the cross bar 19 is a pair of angle-shaped spaced-apart horizontal side rails 20 that are disposed at right angles to the shear bar and attached to end walls 10.

Tubular separators 21 are mounted on side rails 20 and the cross bar 19 is supported thereon, the space thus formed being adapted to accommodate a pair of superimposed valve plates 22 and 23 that span the housing parallel to shear bar 18, the ends being slidably carried above and upon the upper faces of the side rails 20, so that they may be moved at right angles to their spans.

Underlying roll shaft 13 is a rectangular outlet opening 25 for the passage of reduced material, the four marginal edges being defined by cross bar 19, bottom lip 26 of the bottom structure, and side rails 20. Underlying roll shaft 14 is a similar rectangular outlet opening 27 that is defined by overhanging lip 28 which is formed with cross bar 19, lip 29 of the bottom structure, and side rails 20. When the flow of the reduced material is partially interrupted, outlet 25 is then defined by the stationary elements 26, 20—20 and the leading edge of movable plate 22. Likewise, outlet 27 is defined by stationary elements 29, 20—20 and movable plate 23. The areas of the two outlets 25 and 27 are equal and symmetrical with respect to a vertical plane passed midway between axes of the roll shafts, the symmetry remaining constant when the rate of efflux through outlets is varied by valve plates 22 and 23 respectively.

The valve plate 22 is slidably supported upon raised bosses 30 on side rails 20, the upper faces of the bosses being coplanar with lip 26, so that when the plate is moved at right angles to its span toward lip 26, the efflux through outlet 25 is interrupted. The upper face of valve plate 22 is flat and slidably abuts the bottom of cross bar 19. The valve plate 23 is also carried upon the upper faces of the side rails 20, said plate being adapted to interrupt efflux through outlet 27 when moved towards the bottom lip 29. The upper face of valve plate 23 is also flat, it slidably abutting the overhanging lip 28 on cross bar 19 and likewise the overlapping portion of valve

55

plate 22. In other words, the upper face of valve plate 22 is superimposed in a horizontal plane above upper face of valve plate 23.

When the valve plates are positioned so that the outlets are fully closed, the leading edge 31 of plate 22 overlaps lip 26 of bottom structure, and likewise, the leading edge 32 of plate 23 overlaps lip 29, thereby effecting leak-proof closures.

It will be noted that when the valve plates are not fully retracted below cross bar 19, the leading edge and the two end edges of each valve plate are always exposed to the material in which the rolls are submerged. The vertical build-up pressure of material upon the exposed upper faces of the valve plates, due to the downward force of roll teeth, is a factor in preventing any unwarranted movement of the valve plates when the machine is in operation, as such pressure increases the static friction between the valve plates and the supporting rails.

The shear bar 18 and cross bar 19 are secured to the side rails 20 by means of a pair of capscrews 33, that extend upward through openings 34 in the side rails, tubular separators 21, and openings 35 in the cross bar 19, all of which are in alignment with the threaded openings 36 in shear bar with which the capscrews are engaged.

The valve plates are actuated simultaneously in co-ordinated reciprocal relation by means of a pair of rocker arms 37 and 38 on opposite sides of the housing, which arms connect with links 39 and 40 rigidly welded to valve plates 22 and 23 respectively, the ends 41 and 42 being turned upward to make pivotal engagement with the adjacent rocker arms. These rocker arms 37 and 38 are pivoted to a pair of brackets 43 on opposite sides of the housing. To either rocker arm is attached a vertical stem 44 that carries a handle 45 that may be manually operated to impart movement to the valves.

The bearings 12 are secured to the end walls 10 by means of a plurality of machine bolts 46 having heads 47 on the inside of the end walls. Between the lowermost centrally disposed bolt heads 47, the ends of the shear bar 18 are closely seated, thereby rigidly supporting the shear bar so that it may react against any horizontal forces due to impact from the crushing rolls when crushing or shearing material.

To remove the shear bar, which must be replaced when the shearing edges become worn, the capscrews 33 are unscrewed, thereby permitting the shear bar to be raised vertically to free the ends from the seat between the bolt heads 47. To facilitate raising the shear bar, the cross bar 19 is provided with one or more holes 48 directly below the shear bar, these holes being adapted to receive a knockout punch (not shown) for driving the shear bar upward.

In operation, an important feature is the fact that valve plates 22 and 23 always move freely and remain set in any adjusted position, this being the result of two contributing factors, one of which is the build-up pressure of the material above valve plates, whereby the static friction is increased as above explained. The other contributing factor is the tendency of roll teeth to sweep the material over the leading edges 31 and 32 of the valve plates. If the rolls were reversed, so that the material would be forced against the leading edges by action of the moving roll teeth, then the resulting pressure would tend to crowd the valve plates open, thereby destroying the predetermined rate of efflux.

Another outstanding feature is the fact that the rate of efflux from the two outlets is equal regardless of how the valve plates are positioned, and further, the size of the reduced material is same from each outlet. This latter feature makes it practical to employ above described flow-controlling mechanism on any two-roll crushing machine for use in reducing or granulating materials to a predetermined size, the size being varied by adjustment of control handle.

What we claim is:

1. In a machine for reducing material, a housing that receives the material, a bottom structure for the housing having a pair of outlet openings, a pair of downwardly co-acting rolls with teeth for reducing the material, the rolls having shafts journaled in flanged bearings, a plurality of threaded bolts for securing each bearing flange to its supporting wall, said bolts having heads seating against the inside of the wall, a stationary shear bar positioned between the rolls to receive impact from the teeth on the rolls, and means for rigidly supporting the shear bar to react against the vertical and horizontal components of the impact, said means for reacting against the horizontal component comprising the opposite ends of the shear bar seated in metal-to-metal contact between the lowermost adjacent bolt heads.
2. In a machine for reducing material, a housing that receives the material, a pair of downwardly co-acting rolls submerged in the material undergoing reduction, a stationary shear bar mounted between the rolls to receive impact from the roll teeth, a threaded opening in each end section of the shear bar that is adapted to engage a vertical capscrew, means for supporting the shear bar, said means including a cross bar underlying the shear bar in parallel relation therewith and having openings that align with the shear bar openings, means for supporting the ends of the cross bar, said means comprising oppositely disposed side rails carried by side walls of the housing and having openings that align with the shear bar openings, and means for clamping the cross bar between the shear bar and the side rails, said means comprising a pair of capscrews engaging the shear bar and seating against the underside of the side rails.
3. The combination as set forth in claim 2 wherein the cross bar is held in spaced relation above the side rails by means of a pair of tubular separator elements.
4. In a machine for reducing and feeding material, the combination that includes a housing in which is journaled a pair of downwardly co-acting rolls, said rolls having teeth for reducing the material, a stationary element positioned between the rolls to receive impact from the teeth on both rolls, a bottom structure for the housing having a discharge outlet underlying each roll, and flow-controlling means for simultaneously interrupting the efflux from each outlet, said means including a pair of valve plates slidably supported by the housing for horizontal movement below the rolls in inverse relation and in superimposed planes that directly underlie the impact-receiving element.
5. The combination as defined in claim 4 wherein the flow-controlling mechanism includes rotatable interconnected means for retracting the valve plates together to increase the rate of efflux from the machine, said means including a vertical stem with handle.
6. In a machine for reducing and feeding ma-

terial, the combination that includes a housing which receives the material, a pair of downwardly coacting rolls journaled in the housing for reducing the material, said rolls having circumferentially spaced teeth submerged in the material, a bottom structure for the housing, a bottom discharge outlet underlying each roll, each of said outlets being defined by coplanar elements on three sides and on the fourth side by the leading edge of a slidably mounted valve plate, means for supporting the valve plates in superimposed horizontal planes, said means being the upper faces of the coplanar elements in the respective planes, and rotatable means supported by the housing for moving the valve plates in reciprocal coordinated relation to interrupt the effluxes.

7. The combination as defined in claim 6 wherein the rotatable means for moving the valve plates includes a stem which projects upwardly above the housing with a handle mounted thereon.
